WARE.

MECHANICALLY-ACTUATED DIAPHRAGM-HORN.

1,173,584.

Specification of Letters Patent. Patented Feb. 29, 1916.

Application filed June 23, 1911. Serial No. 634,913.

To all whom it may concern:

Be it known that I, JOSEPH W. JONES, a citizen of the United States, and resident of New York city, in the county of New York and State of New York, have invented certain new and useful Improvements in Mechanically-Actuated Diaphragm-Horns, of which the following is a specification.

This invention relates to that class of alarm or signaling devices, especially suitable for use on vehicles, boats, factories and for other purposes calling for the production of a loud, imperative note, in which the sound is generated by a vibratory diaphragm actuated mechanically and preferably by power means.

Such a signal comprises a diaphragm, preferably of spring metal and preferably immovably clamped about its margins, a suitable projector for confining the propagation of the sound to the desired direction and preferably so constructed as to constitute a resonator, driving means of which the preferred embodiment is an electric motor, and suitable mechanical means or connections whereby the rotary movement of the armature or power shaft causes bodily vibratory to and fro movement of the diaphragm such as to produce sound of the desired quality and volume. In the form of signal which has met with the greatest practical success, the diaphragm has been vibrated by rapidly repeated displacements effected by rigidly acting mechanism, a simple and effective embodiment of which has been a rotary cam member mounted rigidly on the rigid and rigidly-supported power shaft and provided with radially acting cam teeth arranged to exert outward thrusts directly on a wear-piece or anvil secured to or formed on the diaphragm. The armature or drive shaft has been arranged parallel to the diaphragm, and the cam shaft has been arranged with its axis eccentric to the axis of the diaphragm and horn. In certain cases also there has been a symmetrical arrangement of horn, diaphragm, and the incased motor, preferably with the motor case substantially concentric and included with the projection of the margins of the diaphragm case.

It is desirable for many purposes that the mechanical means or connections for actuating the diaphragm be not absolutely

rigid, and further that an intermediate connection be interposed between the rotary cam member and the diaphragm, so that the thrust or efforts of the former may be communicated to the latter more or less indirectly. In these ways, the rack and wear on the diaphragm may be greatly reduced. At the same time by the use of a resilient intermediate member which is distinctly stiff, the loudness and urgency of the sound is not materially lessened, and there is sufficient capacity for yielding effectively to guard against damage to the diaphragm in event of the occurrence of serious interference between the moving parts.

A further advantage of the use of an intermediate movable part whether yielding or not is that the efforts impressed upon the diaphragm may be direct outward thrusts with little or no lateral component, so that the twisting or canting effect of a cam tooth acting directly on the diaphragm or diaphragm projection is avoided.

In connection with such an intermediate member I may employ a rotary cam with peripheral teeth, because of the cheapness and durability of such an actuator.

With these objects in view I have designed a mechanically actuated diaphragm horn possessing numerous novel and important features of construction. The rotary actuator is shown herein as a rotary cam with peripheral teeth, and the driving shaft on which it is mounted is preferably arranged perpendicular or at a high angle to the diaphragm, so that the motor may be included within the cylindrical projection of the marginal diaphragm clamps. Between the rotary actuator and the diaphragm I interpose an independently movable member, preferably a lever of the second order. This lever is preferably fulcrumed by being mounted at one end on a stationary support, and extends across the face of the rotary cam member, with a laterally projecting power-receiving portion at its free end disposed across the periphery of the cam member in operative relation to the cam teeth carried thereby, so that the thrusts exerted by the cam teeth in a direction parallel to the diaphragm produce vibration of the central or intermediate portion of the lever to and from the diaphragm. Preferably, the lever is constituted by a stiff

spring tongue having one end clamped immovably to the support, thence extending and engaging across the cam, preferably on the face more remote thereof. Where the 5 rotary cam is formed so as to act radially, the lever may be bent or curved so that its free end portion is disposed opposite the periphery of the cam to receive the thrusts of the cam teeth. Preferably this power- 10 receiving portion is provided with a suitably secured wear-piece or anvil for riding engagement with the cam teeth. Intermediate its ends the tongue or spring lever performs its work to vibrate the diaphragm. 15 A spring lever so formed is admirably adapted to transform the thrusts exerted by the cam teeth radially and parallel to the diaphragm into movement toward the diaphragm at substantially right angles to the 20 direction of thrust. The capacity of the lever to bend slightly and to establish virtual pivots at different points along its length, when the thrust is exerted on the laterally projecting wear-receiving portion, 25 increases the component which is effective in producing vibration of the body portion of the lever to and from the diaphragm and decreases the component which is expended as a pull upon its anchorage. 30 The spring tongue is preferably broad; in some instances it may be as broad or broader than long. In this way I secure stiffness and endurance without rendering the tongue so stiff as to be approximately 35 rigid.

Obviously the body portion of the tongue may contact directly with the face of the diaphragm, but I prefer to provide a contact piece; and in fact both the diaphragm 40 and tongue are preferably so provided. One of the contact pieces may be adjustable with reference to the other; by preference the diaphragm piece is the one adjustable. 45 The tongue or spring lever may constitute either a primary vibrator moving freely between the actuator and the diaphragm and inducing vibration in the latter, or a thrust connection in simultaneous contact with the actuator and diaphragm 50 and capable of changing the direction of thrust. In the first case the spring lever normally stands free of the diaphragm or diaphragm projection and with its power-receiving portion in the path of the cam teeth. The play may be sufficiently large 55 so that the lever does not contact with the diaphragm until after it has been flung clear of the cam tooth, or the lever may touch and commence its forcing of the diaphragm while it is still being forced by the cam. Where the lever is so constructed and arranged as to contact normally with the diaphragm and to intercept the path of the cam-teeth, it is primarily a thrust connection. 60 Where the lever is arranged to stand

normally free of the diaphragm, the diaphragm contact piece may be adjusted laterally so as to touch the face of the lever. Thus the lever may be primarily either a free vibrator or a thrust connection according to the adjustment. Where the lever stands free of the diaphragm contact, its range of free movement may be varied by means of this adjustment of the contact laterally of the lever. This adjustment between the lever and diaphragm also enables me to effect fine adjustment of the lever 70 with relation to the rotary cam, because the component of movement of the power-receiving portion of the lever radially of the actuator when its body portion is forced rearward by the adjusting device operates to vary the degree of interception of the rotary cam and the wear-piece on the lever. This adjustment may be such as to secure 75 most harmonious action between the rotary and vibratory parts. In another case, the lever may be so constituted as normally to stand free of the path of the cam teeth. In this case the adjustment may be employed 80 to bend the spring lever into intercepting relation. It will be obvious, therefore, that the diaphragm and the spring lever may be initially under no tension, a state of elastic 85 stress being produced only under the actuation of the rotary cam, or the adjustment between the two may be such as to maintain them constantly under more or less 90 tension.

In addition to the fine adjustment so provided, I prefer to employ a rougher adjustment, by a construction permitting the tongue or spring lever to be shifted endwise, so as to carry the laterally projecting power-receiving portion toward or from 95 the periphery of the actuator. 100

In the accompanying drawings illustrating the invention by means of a preferred embodiment thereof: Figure 1 is a view partly in side elevation and partly in longitudinal section of a complete signal; Fig. 2 is a front view with the horn and front section of the diaphragm case removed and the spring tongue in section; Fig. 3 is a rear end view with a cap removed; and Fig. 4 is a fragmentary sectional elevation 110 showing a slightly modified construction. 115

In these views, the numeral 10 indicates the diaphragm, which is preferably of thin sheet spring metal, though other material 120 may be used. It is preferably circular in from and immovably clamped about the edges. It is shown as being held in a suitable case, comprising a front section 11 and a rear section 12. These sections have marginal annular clamping portions 13 and 14, between which the edge of the diaphragm is clamped by means of screws 15. The front section is provided with a sound-escape opening, from which extends a suit- 125 130

able projector 16. Preferably this projector or horn is synchronous with the normal operating frequency of the diaphragm, so as to serve as an effective amplifier.

5 The horn is preferably operated by power means, and preferably by an electric motor 17. This motor is inclosed in a case 18, the motor and its case being preferably in the rear of the diaphragm and diaphragm case 10 and preferably symmetrical therewith. As shown, the motor case is inclosed within the cylindrical projection of the diaphragm case and is concentric therewith.

The drive shaft 19, which in the illustrated embodiment is the armature shaft, is preferably arranged at a high angle to the diaphragm, and preferably perpendicular thereto at the center thereof. The shaft is shown journaled near its forward end in 20 a front wall or bridge piece 20 of the motor case and at its rear end in a thrust bearing 21 screwed into a bridge piece 22, which is secured to the rear plate, which in turn is suitably secured to the case. A lock-nut 25 23 serves to hold the thrust bearing at the desired adjustment. Suitable spring-pressed brushes 24 rest on the armature and supply the motor with current, contacts 25 being provided for connection with a supply circuit. The commutator and brushes may be covered by a suitable cap 26, held in place by screws or bolts 27. A lubricating duct 28 may lead from the outside of the case structure through the boss 29 in which the 35 forward bearing of the shaft is formed.

The actuation of the diaphragm is effected from the motor or other source of power through mechanical means. Preferably, I employ a rotary cam 30 mounted on the 40 drive shaft 19. The cam is preferably a disk provided with a suitable number of cam teeth or actuating projections 31. These teeth or projections may be variously formed. In the construction illustrated they 45 are of low pitch on the advancing side and cut away radially at the back.

The cam 30 may be housed in a chamber formed by the rear section 12 of the diaphragm case and an extension of the motor 50 case. In fact, these cases constitute one general case structure. In the particular construction illustrated, the rear section 12 is secured with its back against an outturned flange 33 on the motor case and is provided 55 with a cylindrical flange 34 fitting into the forward extension of the motor case.

The intermediate member 32 is preferably in the nature of a lever. In the best embodiment of the invention it is an independently 60 mounted spring or tongue, constituting a partly yielding lever of the second order. The lever or tongue is supported at one end, thence extends across the face of the cam 30 with its central or body portion opposite 65 the diaphragm, and is provided at its free

end with an offset thrust-receiving portion opposite the periphery of the cam, in position to be engaged by the actuating projections thereof. In this way, the radial movement produced by the thrust of the cam teeth is converted at the central or intermediate portion of the lever into movement toward and from the diaphragm to vibrate the latter. When the lever is a stiff spring it performs this operation to best effect, since 70 its slight yielding enables it to convert a large component of the radial thrusts into movement parallel to the axis of the cam, without transmitting so large a part of the thrust as a pull upon the supported end of the lever. In the particular construction illustrated, the lever is secured at one end to a suitable seat 43 by means of clamping screws 44. The lever thence extends between and across the cam and diaphragm 75 and is shaped so that its free end portion 35 occupies a position opposite the operating face of the cam. In the form of lever shown more particularly in Fig. 1, the body of the lever is curved outward toward the diaphragm, so that the rearward bend of the 80 spring metal of which it is formed is not too abrupt. In Fig. 4, the body part of the lever is substantially parallel to the diaphragm, though this makes the curve or bend at the 85 free end more abrupt. The power-receiving portion of the tongue or lever is preferably provided with a wear-piece or anvil 36, which may be formed on or secured to the lever in any suitable manner. In the particular construction illustrated, it is provided with a threaded shank 37 passed through an opening in the offset portion of the lever, and is secured by a nut 38 and a lock-nut 39 screwed on this shank. Preferably the tongue is broad, as shown in Fig. 2, so that suitable strength and stiffness is imparted to it without prohibitive stiffness or approximate rigidity.

In operation, rotation of the cam 30 110 causes its teeth to force the wear-piece 36 successively outward away from the periphery of the cam. The support or virtual pivot of the tongue or lever and its thrust-receiving portion being not in line with the 115 direction of thrust, and the degree of flexibility possessed by the spring metal, the spring lever is displaced obliquely, the successive thrusts causing the intermediate portion of the lever to vibrate toward and from the diaphragm, so as to vibrate the latter. At their contacting regions, the diaphragm and tongue are preferably provided with contact pieces 40 and 41, respectively. One of these contact pieces is adjustable, and preferably it is the contact piece carried by the diaphragm. In the particular construction illustrated this piece 40 is a screw having threaded engagement in a split sleeve 42 fixed on the diaphragm. The kerfed end 130

of the screw projects from the front of the diaphragm where it may be readily adjusted, and its other end projects through a central opening in the diaphragm.

5 The parts may be so constructed and positioned that the tongue or lever is normally free of the diaphragm but with its wear-piece 36 intercepting the path of the cam teeth. In this instance, the tongue has a 10 certain range of movement under the impulse of the cam tooth before contacting with the diaphragm or its contact-piece. The range of movement may be such that the tongue commences to force the diaphragm while still being forced by the cam tooth, or it may be flung clear of the cam tooth before contacting with the diaphragm, in which event it displaces the diaphragm by virtue of its momentum. Or 15 the tongue may be normally in contact with the diaphragm and with its power-receiving portion in the path of the cam teeth, in which case the tongue acts as a slightly yielding lever thrust connection. Where 20 a certain amount of play is permitted before the tongue contacts with the diaphragm, the range of this movement may be varied by adjustment of the contact-piece 40. In another case, the tongue may 25 normally stand with its thrust-receiving portion out of the path of the actuating projections on the rotary member, and in this instance, the wear-piece 36 can be adjusted into engaging relation to the cam by screwing the contact 40 inward. In any 30 case, this adjusting device carried by the diaphragm may be utilized to secure fine adjustment of the wear piece 36 relative to the periphery of the cam, the rearward 35 movement of the tongue at its body part having a component at the wear piece radial to the cam. In fact, I believe it to be broadly new with myself to provide means on the diaphragm for adjustment between 40 the diaphragm and the mechanical actuating means. Rough adjustment of the tongue I preferably provide for by rendering the tongue longitudinally movable. To this end, I may cause the clamping screws 44 to engage 45 with slots 45 in the tongue, so that by loosening these screws, the tongue may be moved endwise, to carry the wear-piece 36 further into or out of engagement with the cam teeth, after which the screws may be tightened to clamp the tongue in its new position.

The thrust or blow delivered to the diaphragm by the spring lever may be either substantially normal, as in the form shown in Fig. 4, or somewhat oblique, as indicated in Fig. 1.

I claim:

1. In an alarm or signaling device, a diaphragm, a rotary cam provided with peripheral disposed cam projections and dis-

posed with its axis presented endwise to the diaphragm, an independently mounted stiff spring secured to a suitable support at one end, extending across to the more remote face of the cam and having its free end disposed opposite the cam and its intermediate portion arranged in operative relation to the diaphragm.

2. In an alarm or signaling device, a diaphragm, a rotary cam provided with peripheral cam projections and disposed with its axis at a high angle to the diaphragm, and an independently mounted broad spring tongue disposed with its body portion in front of said cam and opposite the diaphragm in actuating relation to the latter and having a thrust-receiving portion offset at its rear side in position to be engaged by said peripheral projections.

3. In an alarm or signaling device, a diaphragm, a power-driven rotary cam provided with peripheral cam teeth and having its axis approximately at right angles to the diaphragm, a spring tongue having its body or central portion disposed opposite the diaphragm, being clamped to a stationary support at one end and provided with an offset thrust-receiving portion at the other end opposite the periphery of said cam, and a contact piece on said diaphragm adjustable 95 toward and from the body or central part of said tongue.

4. In a mechanical horn, a flexible diaphragm, a vibratory impact member normally spaced away from and adapted to be forced into engagement with said diaphragm, an actuating member operating in a constant plane and adapted to engage said impact member and force it into engagement with said diaphragm, said impact member being adapted to automatically return to its normal position within the operative plane of said actuating member and the portion thereof engaging the diaphragm being adapted to pass said normal position 110 under the control of said diaphragm irrespective of the position of said actuating member, and means actuating said actuating member.

5. In a mechanical horn, a flexible diaphragm, a flexible vibratory impact member normally spaced away from and adapted to be forced into engagement with said diaphragm, an actuating member operating in a constant plane and adapted to engage said impact member at a point removed from its point of engagement with the diaphragm and force it into engagement with said diaphragm, whereby the resiliency inherent to said impact member will cause it 125 to automatically assume and return to its normal position and the portion thereof engaging the diaphragm to yield upon the reflex action of the diaphragm so as to pass this normal position independently of the 130

engagement of said actuating member therewith, and means actuating said actuating member.

6. A horn or signaling device including
5 a diaphragm, an annular diaphragm clamping member having a large central aperture, a rotary electric motor having a cylindrical shell, an end wall integral therewith, means for securing said motor to said
10 clamping member with said end wall extending across said aperture, a cam carried by the armature shaft, and a lever having one end carried by the motor and having the opposite end engaging with said cam, and
15 having an intermediate portion for engagement with said diaphragm whereby the removal of the motor from the diaphragm clamping member carries with it said lever.
7. A horn or signaling device including
20 a diaphragm, a diaphragm clamp, a rotary electric motor secured to said clamp including a peripheral shell and an end wall integral with said shell, a removable end wall opposite to said integral end wall, brushes
25 carried by said removable end wall, a detachable cap inclosing said brushes and engaging with the outer terminal portion of said peripheral wall, an armature shaft supported by said end wall and presented end-
30 wise to said diaphragm, and means for vibrating said diaphragm upon the rotation of said shaft.

8. A horn or signaling device, including a diaphragm, a diaphragm clamp, a rotary electric motor including a peripheral wall 35 having one end connected to said clamp, a removable end wall at the opposite end of said peripheral wall, brushes carried by said end wall, an armature shaft having one end supported by said end wall, and presented 40 endwise to said diaphragm, a cup-shaped casing concentric with said motor, and a fastening member extending in the direction of the axis of the motor through said casing into said removable end wall. 45

9. A horn or signaling device, including a diaphragm, a diaphragm clamp, a rotary electric motor including a peripheral wall having one end connected to said clamp, a removable end wall at the opposite end of said peripheral wall, brushes carried by said end wall, a cup-shaped casing concentric with said motor, and a bolt for fastening said casing in position, said bolt extending in the direction of the axis of the motor 50 through the casing into said removable end wall. 55

Signed at New York in the county and State of New York this 22nd day of June A. D. 1911.
